UNITED STATES PATENT OFFICE

146,984

DESIGN FOR A HELICOPTER

Frank N. Piasecki, Lansdowne, Pa., assignor to
Piasecki Helicopter Corporation

Application March 7, 1946, Serial No. 127,207

Term of patent 14 years

(Cl. D71—1)

To all whom it may concern:

Be it known that I, Frank N. Piasecki, a citizen of the United States of America, residing at Lansdowne, in the county of Delaware and State of Pennsylvania, have invented a new, original, and ornamental Design for Helicopters, of which the following is a specification, reference being had to the accompanying drawings, forming a part thereof.

Figure 1 is a side elevational view of a helicopter, showing my new design as it would appear on the ground.

Figure 2 is a front elevational view of the same.

Figure 3 is a rear elevational view of the same.

Figure 4 is a top plan view of the same.

Figure 5 is a partial cross section taken on line 5—5 as shown in Figure 1.

I claim:

The ornamental design for a helicopter, as shown.

FRANK N. PIASECKI.
